(57) **CLAIM**

The ornamental design for a microphone for wireless communication device, as shown and described.

DESCRIPTION

FIG. 1 is a perspective view of a microphone for wireless communication device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines of the drawings represent portions of the microphone for wireless communication device that are not part of the claimed design.
